UNITED STATES PATENT OFFICE.

JOHN A. PRYOR, OF EAST ORANGE, NEW JERSEY.

CENTER ATTACHMENT FOR CHAINS.

1,270,208.

Specification of Letters Patent. Patented June 18, 1918.

Application filed March 1, 1917. Serial No. 151,680.

To all whom it may concern:

Be it known that I, JOHN A. PRYOR, a citizen of the United States, residing at East Orange, in the county of Essex and State of New Jersey, have invented certain new and useful Improvements in Center Attachments for Chains; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference generally to jewelry, and the invention relates, more particularly, to improvements in pocket-to-pocket vest watch chains, and similar chain jewelry.

The invention has for its principal object to provide a center attachment for connecting the center of a chain to a vest or other garment; and the invention has for a further object to provide a very simple and neat, and easily applied attachment means for connecting and retaining in position upon the vest or other garment the suspended center of the chain as it extends from pocket to pocket of the garment; said attachment means also being of such a character that it easily lends itself to ornamentation by jewels or otherwise, so that aside from its utility characteristics it may be used to enhance and beautify the appearance of the chain.

Other objects of the present invention, not at this time more particularly enumerated, will be clearly understood from the following description of the same.

The invention is clearly illustrated in the accompanying drawings, in which:

Figure 1 is a face or front view of the lower portion of a vest or waistcoat showing a pocket-to-pocket watch chain arranged therewith, the same having the novel center attachment means for holding the suspended center of the chain against the vest, and in its retained connection with the latter.

Fig. 2 is an enlarged detached face view of a pocket-to-pocket vest chain (the ends thereof being broken away) provided with the novel center attachment device, made according to and embodying the principles of my present invention.

Fig. 3 is a top edge view of the same, showing the relation of said novel center attachment device to the marginal edge of the vest when operatively connected therewith.

Fig. 4 is a rear face view of the same, illustrating the back of said novel center attachment device.

Similar characters of reference are employed in all of the herein-above described views, to illustrate corresponding parts.

Referring now to the said drawings, the reference character 1 indicates a portion of a vest or waistcoat, provided with the laterally opposite pockets 2 in each front panel thereof. The reference character 3 indicates the marginal edge of the overlapping front panel of the vest, where the same overlaps and buttons upon the other panel of the vest.

The reference character 4 indicates a pocket-to-pocket vest watch chain, made up of interconnected links of any desirable shape or ornamental design. Chains of this character are sometimes known as Walde- 80 mar chains, and the same are adapted to be worn so as to extend between laterally opposite pockets of a vest or waistcoat. These chains are provided on one end with a swivel snap (not shown) for attaching a watch at 85 one end of the chain for insertion in one pocket, and are provided on the opposite end with a spring-ring (not shown) for attaching a knife, cigar-cutter or other article to said opposite end of the chain for inser- 90 tion in the other pocket. As heretofore used these chains have not been provided with any form of attachment for securing the same to the vest or waistcoat, independently of the mere insertion of their ends in said 95 laterally opposite pockets. Consequently these chains, and the articles connected to the end thereof are more readily surreptitiously removed from the person by pickpockets, and, furthermore, as the chain sags 100 across the face of the vest it is very likely to swing away from the vest, when a person wearing the same leans over, so that it is likely to catch against adjacent stationary objects, and in that way may be easily liable 105 to sustain a breaking or damaging strain.

My present invention, among other advantages eliminates the above mentioned objections, and provides a simple and easily manipulated center attachment device for said 110

chains, which secures the same to the marginal edge 3 of the vest or waistcoat without interrupting the neat continuity of extension of the same from pocket to pocket.

5 Said center attachment device comprises a body portion 5 of any desirable shape, size or design. Said body portion 5 is provided at each of its ends with perforated ears or eye-pieces 6. The intermediate links of the chain 4 are attached, respectively, to said perforated ears or eye-pieces 6, so that said body portion 5 is connected longitudinally between said links, so as to be positioned substantially in a central location between the ends 15 of the chain 4, and thus said body-portion practically becomes in itself an interconnected link of the said chain 4. Connected with one end of said body portion 5, at the back thereof, so as to be permanently secured thereto as a part thereof, is a clasp-member, preferably in the form of a longitudinally extending or directed hook-portion 7, the free end 8 of which doubles back longitudinally across the back of said body 20 portion 5, and spaced slightly therefrom. In using the center attachment device, thus constructed, the chain 4 is arranged in the usual manner upon the vest, so as to extend from pocket to pocket, and as thus positioned said body-portion is positioned midway between said laterally opposite pockets and adjacent to the marginal edge 3 of the overlapping panel of the vest. When thus positioned the free end 8 of the hook-portion 30 35 40 45 50 55 60 65 70 75 80 85 90 95 100 105 110 115 120 125 130 135 140 145 150 155 160 165 170 175 180 185 190 195 200 205 210 215 220
